CALL SELECTOR

Filed Jan. 8, 1923

UNITED STATES PATENT OFFICE.

LOUIS L. CHAUVEAU, OF PARIS, FRANCE.

CALL SELECTOR.

Application filed January 8, 1923, Serial No. 611,537, and in France January 17, 1922.

The present invention relates to a new type of call selector. The object of this apparatus is to cause the actuation of a calling device (bell, etc.). The apparatus may be controlled over wires or by means of wireless telegraphy and is responsive to signals composed of groups of impulses of different duration, e. g. letters of the Morse code composed of dots and dashes.

10 The apparatus is so arranged that the calling device is actuated only when the selector receives the predetermined group of signals for which it is adjusted. All other groups of signals, no matter how arranged, do not actuate the calling device.

15 In the following description, the invention is exemplified as applied to a selector schematically illustrated in the drawing. In the drawing, the arrows marked (+) or (-) indicate connections with the (+) and (-) poles, respectively, of a source of electricity, (battery storage battery, generator, etc.) not shown in the drawing.

20 1 is a contact which may be closed manually or by means of any suitable relay (not shown) controlled by a receiver for wireless or wire telegraphy. This contact 1 controls the circuit of relay 2 in such a manner that said relay is energized upon each closure of the contact and while the contact is closed. In response to each one of these impulses the relay 2 is energized through the circuit: from (-), contact 1, relay 2, contact 33, to (+) and closes through its contact 6 the circuit of the controlling relay 8, and the latter being energized, closes its holding contact 9 and the reversing contact 10. As a result of this, upon each closure of contact 1, the relay 8 is energized from minus through contact 6, relay 8 to plus and locks up through its contact 9 from the minus connection associated with relay 11 through contact 26, contact 9, relay 8 to plus. By actuating the contact 10, the circuit of the normally energized slow-release relay 11 is opened. This relay may be of the slow-release type used in automatic telephony and is adjusted in such a manner that its normally open contact 12 is closed only after the expiration of a period of time required for a dot. Therefore, when the contact 12 is closed, the relay 2 has ceased to be energized if the signal received is a dot, but will be still in energized condition if the signal received is a dash. The contact 12 extends the current path to the re-

versing contacts 7 whereby, if the signal received is a dot, current flows through conductor 15, and through conductor 14 if the signal received is a dash. This arrangement constitutes the dot and dash selector. 60

At the same time that relay 11 allows its contact 12, to close, it opens its contact 26 which in turn opens the locking circuit of relay 8. The apparatus is now in condition to select a new signal. It is necessary to arrange for the transfer of the signal, depending on its nature, to its proper circuit and for this purpose the relay 2 is provided with a set of contacts 40. When the contact 1 is opened the contact 40 is in its normal position and closes an energizing circuit from minus to contact 40 on the right hand side, contact 42, relay 41 to plus for the relay 41 which in turn locks up through minus to contact 45, contact 42, relay 41 to plus. The 70 relay 41 closes also the contact 43. 75

When a signal is received the line 46 is connected thru relay 44, contact 43 and the contact 40 with the (-) pole of the battery.

80 Circuit may then be completed thru the line 46 through one of the electromagnets or relays 47, 50, 53 and 56 to the (+) pole, as described below. For example, when the proper initial signal is received, relay 2 is energized by the closing of contact 1 thereby 85 moving all of its movable contacts to the left, and with relay 41 energized as explained above thereby closing contacts 42 and 43, the circuit through relay 47 is as follows: (-), 40 on the left, 43, relay 44, 90 line 46, 68 on the left, relay 47, conductor 58^a, 58, 33 to (+). The relay 44 will then be energized and opens at 45 the locking circuit of the relay 41. The contacts 42 and 43 of this latter relay are opened and the line 46 95 is disconnected from the negative pole at 43.

During the silent period following the receiving of the first signal the relay 41 is again energized. These operations are repeated upon the receiving of each signal and a short current impulse is sent through the line 46 at the beginning of each signal. 100

When the first impulse is sent the line 46 is connected through contact 68 on the left hand side with the relay 47. This relay becomes energized and locks up through its contact 68 on the right hand side to (-). Through its contact 49, the relay 47 connects the relay 50 with the line 46 but in view of the fact that the line receives only very 105 110

short impulses under the control of the relay 44, the relay 50 does not now become energized. It will be energized upon the sending of the next impulse. Relay 47 being locked up through contact 68 on the right hand side to (-) as a result of the first impulse, and contact 49 now being closed, relay 50 will be energized by the following circuit: (-), 40 on the left, 43, relay 44, line 46, 49, conductor 49^a, 51 on the left, relay 50, conductor 58^a, 58, 33 to (+). The relay 50 will then lock up as a result of the second impulse as follows: (-), 51 on the right, relay 50, conductor 58^a, 58, 33 to (+). As a result contact 52 will close and prepare relay 53 for the third impulse, by connecting the relay 53 with the signal line 46.

Upon the sending of the third impulse, relay 53 will be energized by the following circuit: (-), 40 on the left, 43, relay 44, line 46, 52, conductor 52^a, 54 on the left, relay 53, 58, 33 to (+). The relay 53 will then lock up through its contact 54 on the right to (-). At the same time contact 55 will be closed to prepare relay 56 for the fourth impulse by connecting the relay 56 to the signal line 46, through 55, conductor 55^a, 57 on the left, relay 56, conductor 58^a, 58, 33 to (+). The fourth impulse will then energize relay 56, which will lock up through (-), 57 on the right, relay 56, conductor 58^a, 58, 33 to (+).

It will be seen that such arrangement makes possible the successive operation of the electromagnets or relays 47, 50, 53 and 56 in accordance with the arrival of the signals. In order to insure a proper operation it is necessary that the contact 68 be closed as soon as the relay 47 operates and that the contact 49 be closed only at the end of the operation of said relay. The same thing holds good also for relays 50, 53 and 56 and such adjustments may be readily made in the contact springs. It may happen that the relay 44 opens the locking circuit of relay 41 too soon; adjustment of its contact spring will then be required. The contact 43 being opened in response to the successive operation of these two relays, the line 46 will be under current for a sufficient length of time to cause the energization of one of the relays 47, 50, 53 or 56.

In accordance with the operation of relays 47, 50, 53 and 56, the restoring relay 23 is connected through the contacts 17, 18, 19 and 20 either with the dot line 15 or with the dash line 14. If the group for which the apparatus is adjusted is such that the first signal is a dash, the contact 17 is connected to the dot line 15 and the other contacts 18, 19 and 20 are also connected to the line corresponding to the other signal than the one for which the apparatus is adjusted.

It will be seen, therefore that, if the group of signals sent is the one for which the ap-

paratus is adjusted, the contacts 17, 18, 19 and 20 are not traversed by current, whereas if the signal group received does not correspond to the adjustment of the apparatus, one of the above mentioned contacts is traversed by current whereupon the relay 23 becomes energized from the minus connection associated with relay 11, contact 12 either of contacts 7 through contacts 17, 18, 19, 20, through contact 24, through restoring relay 23 to plus and opens in its contact 58 the circuit of the relays 47, 50, 53, 56 and these relays cannot operate unless the signals received belong to the group for which the apparatus is adjusted.

Let us assume that a signal different than the one for which the apparatus is set is received, (it being noted that the figure illustrates the apparatus set for the signal -.-.). Then if the first impulse received is a (.), a short current impulse will be sent through the circuit (-), 40 to the left, 43, relay 44, signal line 46, 68 on the left, relay 47, conductor 58^a, 58, 33 to (+), resulting in relay 47 locking up at 68 to the right to (-), and closing contact 17. At the same time, a short current impulse will be sent through the circuit (-), contact 12, 7 to the right, dot-line 15, contact 17, conductor 17^a, 18, conductor 18^a, 19, conductor 19^a, 20, relay 23 to (+). This causes the energization of relay 23, thus breaking the circuit of relay 47 at 58, and causing the apparatus to be reset to its original setting. Now suppose that the first impulse is correct, namely a (-), and the second impulse is also a (-), the latter being incorrect for the particular setting of the apparatus, then a current impulse will be sent through dash-line 15, contact 18 to the right, conductor 18^a, 19 to the left, conductor 19^a, contact 20, relay 23, to (+), thereby energizing relay 23, which in turn breaks the circuits of relays 47 and 50 at 58, thus restoring the apparatus to its original setting.

The relay 23 is provided with a locking contact 24 which holds it up from minus, contact 28, contact 24, relay 23 to plus as soon as it receives an impulse and until the slow release relay 27 becomes deenergized. This slow-release relay controls the duration of the silent periods in a manner to be described.

Upon the energization of the controlling relay 8 a circuit is closed in the contact 10 for the slow release relay 27 which is provided for the purpose of controlling the duration of the silent periods separating the signals of one and the same group. In response to each signal received the relay 27 becomes energized if the signals received follow each other in normal succession, i. e. if the duration of the silent period separating two consecutive signals is shorter than the time margin of the slow-acting magnet

27, then this slow-acting magnet does not permit its contact 28 to return to normal.

However, if the duration of the silent period separating two signals is longer than or equal to this time, the contact 28 will return to normal and closes through contacts 60 and 20 an energizing circuit for the restoring relay 23 whereupon the apparatus is restored to normal.

10 It will be seen therefore that all silent periods between the signals and before the receiving of the last signal (if they are too long) cause the restoration of the apparatus.

If the signals received belong to the group 15 for which the apparatus is adjusted and if the signals are sent in normal sequence i. e. if they are separated by suitable silent periods, the relays 47, 50, 53 and 56 will operate in the normal manner indicated above. 20 Two things may happen now: either the group of signals received is the one for which the apparatus is adjusted or the group of signals received comprises one more signal than is required by the adjustment of the apparatus.

In the first case the group received will be followed by a longer silent period than the normal silent period separating the signals, the contact 28 of the slow-release relay 30 magnet 27 will return to normal and an energizing circuit will be closed through conductor 29 and the contact 22 for the ringing relay 31. Relay 31 closes contact 33 completing the circuit of the call-bell S. 35 At the same time, the relay 31 locks up through contact 34 to the minus pole until the apparatus is stopped, either by hand or by means of a key 35. When the relay 31 operates, the relay 2 is disconnected from 40 the (+) pole in contact 33. For this reason, the signals that might be sent later on, will not be received until the relay 31 is returned to its normal condition upon the actuation of key 35.

45 The bell will ring until the key 35 is depressed, and during all this time the signals do not actuate the apparatus.

Upon the energization of the ringing relay 31, the contact 33 also disconnects the 50 positive pole from the common return leading to the relays 47, 50, 53, 56 whereupon these relays become deenergized.

In the second case, if the group of signals received is followed by another signal, the 55 contact 21 being closed at this time, the restoring relay will be energized at the beginning of this additional signal and will restore the apparatus to its normal position without causing the actuation of the bell.

60 It will be seen therefore that the calling device cannot be actuated by a group of signals composed of the same signals as the group for which the apparatus is adjusted but comprising an additional signal (dash or dot). In this manner, if the Morse code

is used and the apparatus is adjusted for the letter S (—. . .), it will not respond to the letter H (—. —.) or the letter V (—. —. —.). Further in case of the letter S (—. . .) the device cannot be operated by the letter B (—. —.) as 70 the restoring relay 23 is energized by the first signal (which is a dash) and locks up through its contact 24 and the contact 28 of the slow release relay 27. The relays 47, 50, 53 and 56 are restored to normal until 75 a sufficiently long silent period is produced.

It will be seen, therefore, that when an apparatus is adjusted for a certain group of signals, the calling device does not respond unless the group is normally sent out, i. e. 80 it is neither preceded or succeeded by any signal and the periods for spacing the signals are not too long. In this manner, the system adjusted for a certain group cannot be actuated by elements of other consecutive 85 groups.

The above description was given merely for the purpose of exemplifying the invention, the arrangement disclosed relating to a group of signals corresponding to the letter C (—. . .) of the Morse code. Obviously, 90 the apparatus may be subjected to various modifications or simplifications depending on the particular application desired. The type and construction of the relays or magnets is arbitrary, the main thing being that these relays perform the functions disclosed.

The apparatus may be used to respond to call signals, such as groups of letters in wireless telegraphy for ships or to respond 100 to the S O S signal. In this case the number of the contacts 17 to 20 and relays 47 to 56 will be increased to equal the total number of signals forming the different letters of the call indication.

In the case of transmission over wires, the apparatus may be simplified, whenever possible, by substituting in the place of the Morse code, a code composed of groups comprising a uniform number of signals.

A certain elasticity in the cadence of operation may be obtained by proper adjustment of the slow-release relays 11 and 27 in such a manner that, the contact 1 may be manually controlled. This elasticity may be 115 further increased if the relay 27, instead of controlling the silent periods between each signal, is used for controlling the duration of the whole group (both impulse and silence). Under these conditions, the manipulation may be irregular but the apparatus will respond as long as the signals forming the group are sent out during a time determined by the slow-release relay 27, irrespective of the cadence of manipulation during this time.

In addition to its use as a call selector, this apparatus may be used also as a selector for controlling distant mechanical functions or as a telephone or telegraph selector.

Having described my invention I declare that what I claim is—

1. In combination, a repeating relay, impulse relays actuated thereby, one of which effects a time delay, a signal line connected with the other impulse relay, a series of character relays sequentially associated with the signal line on successive impulses, dot and dash lines associated with the first impulse relay, contacts controlled by the character relays to connect the dot or dash line in predetermined sequence, and means controlled by such connections to restore the character relays when operated out of sequence for which they are arranged. 70
2. In combination, a repeating relay, impulse relays actuated thereby, one of which effects a time delay, a signal line connected with the other impulse relay, a series of character relays sequentially associated with the signal line on successive impulses, dot and dash lines associated with the first impulse relay and controlled by the repeating relay, and means controlled by each character relay for sequentially completing the dot and dash line circuits. 85
3. In combination, a repeating relay, impulse relays actuated thereby, one of which effects a time delay, a signal line connected with the other impulse relay, a series of character relays sequentially associated with the signal line on successive impulses, dot and dash lines associated with the first impulse relay, a restoring relay for opening the circuits to the character relays, a space relay for rendering the restoring relay inoperative, contacts controlled by the character relays for connecting the dot and dash line to the restoring relay in a predetermined sequence whereby the restoring relay will nullify the effect of prior impulses on the character relays whenever an impulse out of sequence occurs. 95
4. In combination, a repeating relay, impulse relays actuated thereby, one of which effects a time delay, a signal line connected with the other impulse relay, a series of character relays sequentially associated with the signal line on successive impulses, dot and dash lines associated with the first impulse relay, a restoring relay for opening the circuits to the character relays, a space relay for rendering the restoring relay inoperative, contacts controlled by the character relays for connecting the dot and dash line to the restoring relay in a predetermined sequence whereby the restoring relay will nullify the effect of prior impulses on the character relays whenever an impulse out of sequence occurs and the space relay will nullify the effect whenever improper spacing occurs. 105
5. In a call selector, means responsive to received impulses, timing means for determining the length of impulses received on the 110
6. A call selector having a call circuit adapted to be energized when signal impulses for which the selector is adjusted is received, comprising, means responsive to received signal impulses, timing means for determining the length of the impulses received on the impulse responding means, a conductor and means whereby it is arranged to be energized whenever an impulse is received by the impulse responding means, a plurality of relays connected to said conductor and arranged to be energized sequentially only upon receipt of the signal impulses for which the selector is adjusted, means associated with the timing means and with the character relays for nullifying the effect of prior impulses on the relays when other impulses are received on the responding means, and means controlled by the last of said relays to prepare the call circuit for energizing an indicator. 120
7. In a call selector, means responsive to received impulses, timing means associated therewith for determining the length of the impulses received on the impulse responding means, a plurality of line-conductors and means whereby one of said conductors is arranged to be energized whenever an impulse is received, means including the timing means whereby another of said conductors is arranged to be energized whenever the received impulse is a dot and means including the timing means whereby the third conductor is arranged to be energized whenever the received impulse is a dash, a plurality of relays, the number of said relays corresponding to the number of impulses in the call to be selected, means whereby said relays are arranged to be connected in sequence to said first mentioned conductor on the receipt of successive impulses, means associated with the relays and with the dot and dash line-conductors in such manner that when a relay and either the dot or the dash 125
- 65

line-conductor are simultaneously energized, the selector will return to normal, and means controlled by the last of said relays for preparing a circuit for energizing an indicating device.

8. In a call selector adjusted to respond to desired signal impulses, in combination, means responsive to received impulses, timing means associated therewith for determining the length of impulses received on the impulse responding means, a plurality of relays associated with the impulse responding means energized in a predetermined sequence on the receipt of desired signal impulses, means controlled by said relays and said timing means for restoring the selector to normal on the reception of an undesired signal impulse, and means controlled by the last of said relays to prepare a circuit for energizing an indicator.

9. In a call selector adjusted to respond to desired signal impulses, in combination, means responsive to received impulses, timing means associated therewith for determining the length of impulses received on the impulse responding means, a plurality of relays associated with the impulse responding means energized in a predetermined sequence on the receipt of desired signal impulses, means controlled by said relays and said timing means for restoring the selector to normal on the reception of an undesired signal impulse, means controlled by the last of said relays to prepare a circuit for energizing an indicator, and a second timing means for completing said circuit on the expiration of a predetermined silent period after the termination of the last impulse as received on the impulse responding means in the sequence for which the selector is adjusted.

10. A call selector adjusted to respond to desired signal impulses, comprising means responsive to received signal impulses, a signal line conductor energized whenever an impulse is received through said means, a plurality of relays associated with said signal line conductor and arranged to be energized in a predetermined sequence only upon the reception of the desired signal impulses,

means controlled by said relays and said timing means for restoring the system to normal on the reception of an undesired signal impulse, means controlled by the last of said relays for preparing a circuit for energizing an indicator, and a slow releasing relay associated with said signal responsive means for restoring the system to normal at the expiration of a predetermined silent period after the termination of any signal impulse except the last impulse of the predetermined sequence, said slow releasing relay completing the circuit for energizing the indicator at the expiration of a predetermined time after the termination of the predetermined sequence of desired signal impulses.

11. In a call selector for indicating the reception of certain desired predetermined signal impulses, in combination, means responsive to received signal impulses, a series of relays associated with the signal responsive means equal in number to the total number of desired signal impulses, means for consecutively energizing each of said relays upon the reception of desired signal impulses in sequence, a call circuit, and means actuated by the last relay for closing the call circuit.

12. In a call selector for indicating the reception of certain desired predetermined signal impulses, in combination, means responsive to received signal impulses, a series of character relays associated with the signal responsive means equal in number to the total number of desired signal impulses, means for consecutively closing a circuit through each character relay upon the reception of desired signal impulses, a call circuit and means actuated by the last character relay for closing the call circuit, circuit breaking means associated with a common portion of each character relay circuit, and means associated with each character relay for actuating the circuit breaking means upon the reception of an undesired signal impulse, thus preventing the operation of the call circuit.

LOUIS L. CHAUVEAU.
